WINDOW SHADE ROLLER MECHANISM

Filed Oct. 6, 1921

Inventor

Benjamin H. Tidy.
by Benjamin H. Tidy
Atty.

UNITED STATES PATENT OFFICE.

BENJAMIN HARRY TIDY, OF BRANTFORD, ONTARIO, CANADA.

WINDOW-SHADE-ROLLER MECHANISM.

Application filed October 6, 1921. Serial No. 505,868.

To all whom it may concern:

Be it known that I, BENJAMIN HARRY TIDY, a subject of the King of Great Britain, and a resident of the city of Brantford, 5 in the county of Brant, Province of Ontario, Dominion of Canada, have invented certain new and useful Improvements in Window-Shade-Roller Mechanism, of which the following is a specification.

10 My invention relates to improvements in window shade roller mechanism and the object of the invention is to provide an inexpensive mechanism for controlling the rotation of the roller and for enabling the 15 shade to be raised and lowered and locked in any partially raised position without the necessity of handling the shade in any way.

My invention consists of the construction and arrangement of parts, all as hereinafter 20 more particularly described and illustrated in the accompanying drawings in which;

Fig. 1 is a front elevation of my invention the roller being broken away intermediate of its length to economize space.

25 Fig. 2 is a side view of the left hand roller supporting bracket.

Fig. 3 is a side elevation looking in the direction of the arrow in Fig. 1, the roller being shown in section on the line 3, 3.

30 Fig. 4 is a detail view showing the connection of a spool to the end of the roller.

Fig. 5 is a side view of the right hand roller supporting bracket.

Fig. 6 is a view of the brake lever used 35 in my invention a detachable brake shoe carried thereby being omitted.

In the drawings like characters of reference indicate corresponding parts in the different views.

40 1 and 2 are roller supporting brackets in which the roller 3 is rotatably mounted after the usual manner.

45 4 is a spool concentrically secured to the right hand end of the roller by means of the screws 5.

This roller carries a circular flange 6 having a smooth peripheral edge.

7 is a brake lever pivotally mounted intermediate of its length upon the bracket 50 2 by means of the pin 8.

This brake lever is provided at its lower end with a bent flange 9 which is provided with an orifice 10.

55 11 is a wedge shaped rubber brake shoe secured within a grip 12 formed on the upper end of the brake lever.

13 is a stop formed on the bracket 2, the purpose of which will appear hereinafter.

14 is an operating cord, one end of which is secured to the spool 4, the free end of the 60 cord passing freely through the orifice 10 in the flange 9 and being freely suspended therebelow.

The operation of my invention is as follows:

The normal position of the brake lever 7 is shown in Fig. 3.

In this position the lever is disposed in a forwardly and downwardly inclined position, the brake shoe 11 being gravity held 70 in engagement with the smooth peripheral edge of the spool flange 6, the point of contact of the brake shoe with this flange being indicated at 15.

The operating cord 14 passes from the 75 spool 4 in a downwardly inclined direction through the orifice 10 from which it hangs freely vertically.

It will be noted that the point of contact 15 of the brake shoe with the flange 6 and the point at which the cord 14 passes through the orifice 10 lie on opposite sides both vertically and horizontally of the axis of the spool and roller.

From the above it will be apparent that 80 normally the brake shoe 11 is gravity held in frictional contact with the spool flange 6 and therefore acts as a brake preventing rotation of the roller.

The flange 6 constitutes a brake element 90 carried by the roller.

When it is desired to raise or lower the curtain it is simply necessary to pull downwardly upon the cord 14. This downward pull oscillates the brake lever clockwise, the tendency being to straighten out the cord and move the lower end of the lever inwardly in the direction of the arrow in Figure 3.

This disengages the brake shoe 11 from 100 operative contact with the flange 6.

Continued downward pulling upon the cord 14 will wind the curtain upon the roller.

To secure the curtain in any position it is 105 simply necessary to release the cord 14 which permits the brake lever to return by gravity to the position illustrated in Fig. 3 with the brake shoe operatively engaging the flange 6.

To lower the curtain the cord 14 is pulled 110 downwardly thus oscillating the lever as above described and releasing the brake.

By letting the cord slip through the fingers and keeping it stretched so as to lie in a straight line, the brake lever is held in the raised position with the brake released and the curtain may be allowed to fall to any desired point at which it may be locked by simply releasing the operating cord which again permits the brake lever to return by gravity to its operative position in Figure 3. 10 The stop 13 engages the brake lever and limits its oscillation backwardly. This is in order to prevent the lever from falling completely over in the wrong direction.

I am aware that ratchet devices have been used in connection with curtain rollers, but my invention uses a brake shoe having frictional rubbing contact with a smooth brake element carried by the roller.

A feature of my invention is the use of the wedge shaped rubber brake shoe 11 which, while providing a very secure brake upon the roller is practically self adjusting as to wear and may be quickly and inexpensively replaced.

From the foregoing it will be evident that I have devised valuable improvements in window shade roller mechanism which while being inexpensive will be very efficient in use.

What I claim as my invention is:

In a window shade roller mechanism, the combination with a roller having its ends journaled in supporting brackets, and a cur-

tain wound thereon, of a spool rigidly carried by the roller at one end thereof and comprising a circular flange having a smooth metallic peripheral edge, a single operating cord having one end secured to the spool, a brake lever pivotally mounted intermediate of its length upon the roller supporting bracket, a wedge shaped rubber brake shoe carried at the upper end of the lever, the free end of the operating cord passing freely through an orifice in the lower end of the brake lever and suspended freely therebelow, the brake lever normally gravity held in a forwardly and downwardly inclined position in which the brake shoe is in frictional rubbing engagement with the aforesaid smooth peripheral edge of the circular flange of the spool and in which the point of contact of the brake shoe with said flange, and the orifice in the lower end of the brake lever, lie on opposite sides, both vertically and horizontally of the axis of the spool, and a stop carried by the roller supporting bracket, said stop projecting into the path of oscillation of the brake lever and adapted to engage the rear side thereof for limiting the oscillation of the brake lever away from the spool.

BENJAMIN HARRY TIDY.
